SEAM RIPPER

Herman Ament, 60 Marbledale Road,
Tuckahoe, N.Y. 10707

Filed Feb. 28, 1972, Ser. No. 230,187

Term of patent 14 years

Int. Cl. D3—99

U.S. Cl. D3—19 A

FIG. 1 is a side elevational view of a seam ripper showing my new design.

FIG. 2 is an exploded side elevational view thereof taken at 90° angle from that of FIG. 1.

FIG. 3 is a bottom end view thereof.

FIG. 4 is a top end view thereof.

The sides opposite those illustrated are identical to those shown.

I claim:

The ornamental design of a seam ripper, substantially as shown and described.
